(57) **CLAIM**

We claim, the ornamental design for a catheter head, as shown and described.

DESCRIPTION

FIG. 1 is a top perspective view of a catheter head illustrating our new design;

FIG. 2 is a top view of the design of FIG. 1;

FIG. 3 is a side view of the design of FIG. 1;

FIG. 4 is a bottom view of the design of FIG. 1;

FIG. 5 is a side view of the design of FIG. 1;

FIG. 6 is a front view of the design of FIG. 1; and,

FIG. 7 is a rear view of the design of FIG. 1.

The broken line represents portions of the structure that form no part of the claim. The dot-dashed line of FIG. 7 represents a boundary line that, and the surface area within, form no part of the claim.
